Primary Examiner — Kimberly Barnes*Assistant Examiner* — Alexandria Dubus(57) **CLAIM**

The ornamental design for a neck pillow storage case as shown and described.

DESCRIPTION

FIG. 1 is a top front perspective view of a neck pillow storage case showing my new design;

FIG. 2 is a bottom view of the neck pillow storage case;

FIG. 3 is a top view of the neck pillow storage case;

FIG. 4 is a right side view of the neck pillow storage case;

FIG. 5 is a left side view of the neck pillow storage case;

FIG. 6 is a front view of a neck pillow storage case; and,

FIG. 7 is a rear view of the neck pillow storage case.

The broken lines depict stitching that form no part of the claimed design.
